T. J. HAYES,
BELT PUNCHING TOOL,
APPLICATION FILED OCT. 9, 1916.

1,231,020.

Patented June 26, 1917.

UNITED STATES PATENT OFFICE.

THOMAS J. HAYES, OF BOSTON, MASSACHUSETTS.

BELT-PUNCHING TOOL.

1,231,020.

Specification of Letters Patent. Patented June 26, 1917.

Application filed October 9, 1916. Serial No. 124,465.

To all whom it may concern:

Be it known that I, THOMAS J. HAYES, a citizen of the United States, residing at Boston, in the county of Suffolk and State 5 of Massachusetts, have invented new and useful Improvements in Belt-Punching Tools, of which the following is a specification.

This invention relates to tools for cutting off the ends of round leather belting to form square ends adapted to be abutted together, for punching the belting near said ends to form holes for the reception of the legs of a staple-shaped wire coupling, and 10 for clenching the legs of the coupling upon adjacent ends of the belting. A tool of this character in common use comprises a pair of body members having opposed faces between which the belting is grasped, and crossed 15 levers fulcrumed together between the jaws, and so connected with the jaws that the faces thereof are moved toward and from each other by the levers and are maintained in parallelism with each other, one of the 20 members being provided with a perforating punch and with a cutter projecting inwardly from the member and coöperating with a shearing edge at one end of a belt-receiving recess in the other member in cutting off the 25 end of a length of belting interposed between the members, the members being provided with extensions formed to coöperate in 30 clenching the belt coupling.

My Patent 1,179,830, dated April 18, 1916, 35 discloses among other things a spring-pressed stripper bridging a belt-receiving recess in one of the members and adapted to bear yieldingly on a belt therein, said stripper being formed to centralize a belt in said 40 recess.

The object of the present invention is to provide certain improvements in the stripper and in the means for connecting the same with one of the body members, where- 45 by the construction is simplified, the operation is improved and the assemblage and separation of parts are facilitated.

The invention consists in the improve- 50 ments which I will now proceed to describe and claim.

Of the accompanying drawings forming a part of this specification:

Figure 1 represents a side elevation of a

tool embodying the invention, the body members being open; 55

Fig. 2 represents a similar view, the members being closed;

Fig. 2^a represents a section on line 2^a—2^a of Fig. 2;

Fig. 3 represents an end view of the tool 60 as represented by Fig. 1;

Fig. 4 represents an enlarged section on line 4—4 of Fig. 1;

Fig. 4^a represents a view similar to Fig. 4, showing the members closed and the 65 punch projected into a belt;

Fig. 5 represents a section on line 5—5 of Fig. 3;

Figs. 5^a, 5^b, 5^c, represent fragmentary 70 sectional views illustrating the coöperation of the stripper with belts of different sizes;

Fig. 6 represents a fragmentary perspective view illustrating a portion of one of the members;

Fig. 7 represents a section on line 7—7 of 75 Fig. 2;

Fig. 8 represents a perspective view of the stripper detached;

Fig. 9 represents a perspective view of the part hereinafter called the yoke;

Fig. 10 represents a perspective view of the part hereinafter called the spring button;

Fig. 11 represents an edge view of a portion of one of the body members and the 85 gage attached thereto.

The same reference characters indicate the same or similar parts in all the views.

In the drawings, 12 and 13 represent the body members of a belt-cutting and punch- 90 ing tool, said members being termed for convenience of description the lower and the upper member respectively, although it is obvious that the tool may be used with either member uppermost. 14 and 15 represent 95 crossed levers fulcrumed together at 16 between the body members, each lever having a longer and a shorter arm. The shorter arms of the levers are connected with the members by pivot studs 17, located in sockets 100 in the members formed to closely fit the studs. The longer arms of the levers are engaged with the members by studs 18, located in longitudinal slots 19 in the members, the arrangement being such that when the 105 levers are moved from the position shown

by Fig. 1 to that shown by Fig. 2, the members are closed and are constantly maintained parallel with each other. The members are provided with coupling-clenching extensions 12^a and 13^a adjacent to the punch.

5 The construction thus far described is well known and is not claimed by me, this embodiment of my invention relating to the punching, stripping and centralizing means 10 hereinafter described.

10 The member 12 is provided with a belt-receiving recess 29, which opens at the inner side of the member, projecting lips or flanges 30 being preferably provided at opposite sides of the mouth of said recess.

15 The stripper is composed of a block 31 formed to closely fit and slide in the mouth portion of the recess 29, said block having a concave face 32 formed to conform to the 20 curvature of one side of a circular belt 33^a inserted in the recess 29.

25 On opposite ends of the block 31 are formed parallel arms 33 provided with longitudinal slots 34. Said arms are formed to overlap and are adapted to slide upon the sides of the member 13 and are preferably provided with curved loops 36 surrounding openings through which the belt passes.

30 37 represents a substantially U-shaped yoke the side arms of which overlap and are in sliding contact with the arms 33 and are provided with orifices 38 receiving studs 39 which enter the slots 34, said studs permitting the arms 33 to slide in contact with the 35 sides of the member 13.

40 40 represents a punch which extends through an orifice 41 in the member 13 and into an orifice 42 in the stripper 31.

45 43 represents a tubular bushing externally threaded and engaged with an internally threaded socket formed in the member 13, the punch extending through the bore of said bushing, which is hereinafter referred to as a spring abutment.

50 45 A spring 44 interposed between the abutment 43 and the stripper 31 exerts a yielding pressure on the stripper tending to force it yieldingly into the belt-receiving recess 29 when the members are closing. The abutment 43 has a reduced cylindrical end portion 45 which enters a circular orifice 46 formed in the neck portion of the yoke 37. The punch 42 projects upwardly from the abutment 43 and is externally threaded and 55 engaged by a nut 47, which when screwed to place is seated on the neck portion of the yoke 37.

60 The belt 33^a is inserted in the recess 29 when the members are open, the stripper being then retracted so that its concave face and a portion of the wall of the recess 29 form a complete circle, as indicated by Fig. 5. As the members close the stripper is pressed yieldingly by the spring 44 against 65 one side of the belt and securely clamps and

centralizes the same just before the advancing punch enters and perforates the belt. By reference to Figs. 5^A, 5^B and 5^C, the action of the stripper in conforming to belts of different sizes will be readily understood.

70 When the members are closed and the nut 47 is removed, the yoke 37 is free to be disengaged from the abutment 43 and from the projecting inner end of the punch and displaced, as indicated by dotted lines in Fig. 2, said yoke and the stripper being then free to be entirely withdrawn from the members, after which the abutment 43 may be withdrawn from the member 13, said abutment being provided with a slot 48 Fig. 10 adapted to engage a tool whereby the abutment may be rotated to unscrew it from its socket.

75 It will now be seen that provision is made for quickly and conveniently installing the punch and the stripper, and for removing 80 the same. The outer end of the punch may be slotted as shown at 49 to permit it to be rotated by a screw-driver for the purpose of longitudinally adjusting the punch.

85 50 represents a gage adjustably secured 90 to the member 12 by a clamp screw 51 passing through a slot 52 (Fig. 11) in one arm of said gage, which is substantially L-shaped. The outer arm of the gage 50 stands opposite the belt-receiving opening 29 and constitutes an abutment for the end of the belt 33^a, as indicated by Figs. 4 and 4^A. The slot 52 and clamping screw 51 enable the gage to be adjusted at different distances from the path of the punch, so that the holes made 95 in the belt by the punch may be located at a distance from the cut end of the belt in proportion to the diameter of the belt, and the length of the staple used to couple the belt together. There are usually three sizes 100 of circular belts, so that provision is required for locating the gage in three different positions. To facilitate the adjustment of the gage, I provide its inner arm with marks 53 (Fig. 11), and the member 12 with 105 a single mark 54 (see Fig. 11).

110 The member 13 is provided in its inner face with a recess 55 (Fig. 5) adapted to receive the stripper 31 and the ears or flanges 30 when the members are closed.

115 The punch 40 has a chisel cutting edge 40^a on its forward end, and its threaded rear end portion is engaged with an internal thread in the spring abutment 43. When the nut 47 is loosened or removed, the punch may be 120 rotated in the abutment 43 to longitudinally adjust its cutting edge and compensate for wear thereof. The cutting edge 40^a should extend parallel with the axis of the belt and not crosswise thereof, because the hole formed in the belt by the punch has a maximum diameter equal to the length of the edge 40^a. No material is removed from the belt by the punch, the material displaced by the beveled sides of its cutting edge tends 125 130

ing to contract and reduce the diameter of the hole in one direction. It will be seen therefore that, if the cutting edge extended crosswise of the belt, the belt would be ob-
 5 jectionably weakened by the punched hole particularly in the smaller sizes. The screw-
 thread engagement between the punch and the abutment 43 enables the punch to be conveniently adjusted to locate the cutting
 10 edge parallel with the axis of the belt, and the nut 47, when turned up against the yoke 37, acts to lock the punch in its adjusted position and also acts to lock and prevent rotation of the abutment 43, the reduced
 15 portion 45 being narrower than the wall of the orifice 46, so that the nut bears only on the yoke and causes the outer end of the abutment to bind on the inner side of the yoke. Provision is therefore made for
 20 accurately adjusting the punch both longitudinally and axially, and for securely holding it at any adjustment.

To maintain the punch in exact alinement with the hole 56 formed for its reception in the member 12, I provide a guide member 24 which, as here shown, is a knife having a cutting edge 26 coöperating with a shearing edge on the member 13. The member 13 has a flat recessed side 22 (which incidentally intersects the wall of a belt-receiving recess 21 to form a shearing edge,) and opposed parallel guiding shoulders 23 projecting from said recessed face. The guide member 24 is rigidly attached at one end to the body member 12 by screws 25, and extends from the member 12 onto the recessed face 22. The flat inner side of the guide member 24 is in sliding contact with the recessed face 22, and the parallel longitudinal edges of the guide member are in sliding contact with the shoulders 23. The flat outer side of the knife is in sliding contact with one of the shorter arms of the lever 15, as best shown by Fig. 7. The face 22 and shoulders 23 contact with three sides of the guide member 24 and the shorter arm of the lever 15 contacts with the fourth side of said member.

The sliding engagement of the guide member 24 with the face 22, shoulders 23 and lever 15, and the rigid attachment of the inner end portion of said guide member with the body member 12, maintains the body members in exact alinement with each other and prevents either member from being deflected laterally from its path of movement. The punch is therefore, maintained in exact alinement with the hole 56.

Having described my invention, I claim:

60 1. A tool of the character stated, comprising an upper and a lower body member, the lower member having a belt-receiving recess, a punch carried by the upper member and arranged to enter said recess and perfor-
 65 ate a belt inserted therein, a belt central-

izing stripper movable in said recess and perforated to receive the punch, connections between said stripper and the upper body member organized to force the stripper yieldingly against the belt when the body 70 members are closing and to positively withdraw the stripper from confining engagement with the belt when the body members are opening, the stripper conforming automatically to the diameter of the belt, and operating means maintaining the body members parallel. 75

2. A tool of the character stated, comprising an upper and a lower body member, the lower member having a belt-receiving recess, a punch carried by the upper member and arranged to enter said recess and perforate a belt inserted therein, a belt centralizing stripper movable in said recess and perforated to receive the punch, slotted arms 80 on opposite ends of the stripper in sliding contact with the body members, a yoke having studs in sliding engagement with the slots of said arms, separable connections between the yoke and the upper member, a spring seated at one end on an abutment in the upper member and at the opposite end on said stripper, and normally holding the members separated and the stripper at the outer portion of said belt-receiving recess, 90 the yoke being displaceable when disconnected from the upper member and removable with the stripper from said members, and operating means maintaining the members parallel. 95

3. A tool of the character stated, comprising an upper and a lower body member, the lower member having a belt-receiving recess, punch-supporting means carried by the upper member, a chisel-edged punch rotatively engaged with said means and adjustable by rotation to determine the position of its cutting edge and compensate for wear thereof, punch-confining means carried by the upper member and including a nut 100 engaged with the punch, and operating means maintaining the members parallel. 105

4. A tool of the character stated, comprising an upper and a lower body member, the lower member having a belt-receiving recess an internally threaded bushing carried by the upper member and engaging an external thread on the punch, the punch being adjustable by rotation to determine the position of its cutting edge and compensate 110 for wear thereof, punch-confining means carried by the upper member and including a nut engaged with the punch, and operating means maintaining the members parallel. 115

5. A tool of the character stated, comprising an upper and a lower body member, the lower member having a belt-receiving recess, a chisel-edged punch carried by the upper member and arranged to enter said re- 120

cess and perforate a belt inserted therein, a belt centralizing stripper movable in said recess and perforated to receive the punch, slotted arms on opposite ends of the stripper in sliding contact with the members, a yoke having studs in sliding engagement with the slots of said arms, a tubular internally screw-threaded spring abutment detachably engaged with the upper member and with said yoke, the punch being extended through said abutment and having a threaded portion engaging the internal thread of the abutment and projecting therefrom, a nut engaged with said threaded portion and seated on said yoke, a spring seated at one end on said abutment and at the opposite end on said stripper, and operating means maintaining the members parallel, the punch being adjustable by rotation to determine the position of its cutting edge and compensate for wear thereof, and maintained in adjusted position by the nut.

6. A tool of the character stated, comprising an upper and a lower body member, the lower member having a belt-receiving recess, a punch carried by the upper member and arranged to enter said recess and perforate a belt inserted therein, a belt centralizing stripper movable in said recess and

perforated to receive the punch, connections between said stripper and the upper member organized to force the stripper yieldingly against the belt when the members are closing and to positively withdraw the stripper from confining engagement with the belt when the members are opening, the stripper conforming automatically to the diameter of the belt, operating means maintaining the members parallel, an adjustable gage carried by the lower member and arranged to support the end of a belt inserted in said recess, and means for confining said gage at different distances from the path of the punch.

7. A tool of the character stated, comprising a pair of body members one member having a belt-receiving recess, a punch carried by the other member and arranged to enter said recess, operating means maintaining the members parallel, and a guide member rigidly attached to one of the body members and in longitudinally sliding engagement with the other body member, means being provided for confining said guide member against lateral movement, and thereby similarly confining the punch.

In testimony whereof I have affixed my signature.

THOMAS J. HAYES.
